UNITED STATES PATENT OFFICE.

THOMAS HIPWELL, OF LONG ISLAND CITY, ASSIGNOR TO THE MANHATTAN BRASS COMPANY, OF NEW YORK, N. Y.

LAMP-BURNER.

SPECIFICATION forming part of Letters Patent No. 480,404, dated August 9, 1892.

Application filed February 25, 1892. Serial No. 422,755. (No model.)

To all whom it may concern:

Be it known that I, THOMAS HIPWELL, a citizen of the United States, residing at Long Island City, (Astoria,) in the county of Queens 5 and State of New York, have invented an Improvement in Lamp-Burners, of which the following is a specification.

Lamp-chimneys have heretofore been formed with a bulb and with a nearly-cylindrical base to rest upon the chimney-support and to be held in position by external chimney-springs, and chimneys of this character have sometimes been made with a flattened bulb, the flattening being in the direction in 15 which the flat flame is spread, in order that such flame may not come into contact at its edges with the glass of the chimney.

With chimneys having flattened bulbs and round or cylindrical bases difficulty has been 20 experienced in insuring the proper position of the chimney to the metallic portions of the burner, and when such chimney is carelessly placed upon the burner the flame is liable to come in contact with such chimney and break 25 the same.

The object of the present invention is to prevent a chimney being misplaced upon the burner; and with this object in view I provide around the cone or deflector a flange or 30 rim notched at opposite edges, and the lamp-chimney is provided with inwardly-pressed guide-ribs at opposite sides of the chimney and in such relation to the flattened bulb that the chimney cannot be misplaced upon the 35 burner, because the chimney cannot be set down upon the chimney-rest until it is in the proper position for the inwardly-pressed guides to coincide with and pass into the notches of the annular flange around the 40 burner.

In the drawings, Figure 1 is a plan view of the burner and a section of the chimney at the line $\alpha\alpha$, and Fig. 2 is a vertical section of the burner and of a portion of the chimney.

45 The burner is of any desired character. I have represented the wick-tube A as surrounded by an air-distributer B and a cone or deflector C, and the chimney-rest D is around the air-distributer B and provided 50 with chimney-springs E, and the annular

flange F surrounds the cone or deflector C, and it may be either plain or perforated, and there are at opposite edges of the annular flange F notches 2, and the glass chimney G has a cylindrical or nearly-cylindrical base 3 to rest 55 upon the chimney-support D and be held by the springs E, and the bulb portion 4 of the chimney is flattened, so as to be adapted to receiving the flattened flame of the lamp as it is spread within the chimney, and upon the 60 cylindrical portion of the chimney-base and at opposite sides thereof there are inwardly-pressed guides 5, adapted to fit loosely the notches 2 in the annular flange F, and these notches and the inwardly-pressed guides are 65 placed in relation to the flat wick in such a way that the flattened bulb of the chimney will have its longest axis in the plane of the flat wick-tube, and should there be an effort to put the chimney on when the flattened 70 bulb is not in proper position for the flame the lower ends of the inwardly-pressed guides 5 would rest upon the annular flange F, so that the chimney could not be passed down upon the chimney-rest until it had been sufficiently rotated to bring the inwardly-pressed guides 5 into line with the notches 2.

This improvement enables me to make use of a flattened-bulb chimney with a flat wick-burner and flame without the risk of the flame 80 coming into direct contact with the flattened bulb of the chimney.

I claim as my invention—

1. The combination, with the lamp-burner having a flat wick-tube and a cone or deflector, 85 of an annular flange around such cone or deflector, having notches at opposite edges thereof, and the flattened-bulb glass chimney having a nearly-cylindrical base and inwardly-pressed guides at opposite sides thereof to 90 pass into the notches of the annular deflector, substantially as set forth.

2. The combination, with the flat wick-burner having a perforated air-distributer, chimney-rest, and springs, of a cone or deflector, an annular flange around such cone or deflector and attached thereto and having notches in the opposite edges, and a flattened-bulb glass chimney having inwardly-pressed guides at opposite sides to the base thereof, 100

adapted to be received into the notches of the annular flange, substantially as set forth.

3. The combination, with the flat lamp-wick burner and its cone or deflector, of an annular flange fastened to such cone and having a notch in the edge thereof and a chimney having a flattened bulb and an inwardly-pressed guide adapted to be received into the notch

of the annular flange, substantially as set forth.

Signed by me this 20th day of February, 1892.

THOMAS HIPWELL.
